FACADE FOR AN ELECTRIC HUMIDIFIER

Ronald B. Kemnitzer, East Lansing, Mich., assignor to
Sunbeam Corporation, Chicago, Ill.

Filed Jan. 10, 1974, Ser. No. 432,413

Term of patent 14 years

Int. Cl. D23—04

U.S. Cl. D23—146

FIG. 1 is a perspective view of a facade for an electric humidifier embodying my new design, the humidifier being shown in broken lines for illustrative purposes only;

FIG. 2 is an enlarged vertical sectional view taken along line 2—2 of FIG. 1;

FIG. 3 is an enlarged horizontal sectional view taken along line 3—3 of FIG. 1; and

FIG. 4 is an enlarged partial front elevational view showing in greater detail the pattern of the screen-effect panel.

The fragmentary pattern of the screen-like panel in FIG. 1 is understood to extend uniformly across the length and width of each panel area.

I claim:

The ornamental design for a facade for an electric humidifier, as shown and described.
